(57) **CLAIM**

The ornamental design for an irrigation drip assembly with a cap having threading stop as shown and described.

DESCRIPTION

FIG. 1 is a perspective view of the irrigation drip assembly with a cap having threading stop;

FIG. 2 is a front elevational view of the irrigation drip assembly with a cap having threading stop;

FIG. 3 is a back elevational view of the irrigation drip assembly with a cap having threading stop;

FIG. 4 is a right side elevational view of the irrigation drip assembly with a cap having threading stop;

FIG. 5 is a left side elevational view of the irrigation drip assembly with a cap having threading stop;

FIG. 6 is a top plan view of the irrigation drip assembly with a cap having threading stop;

FIG. 7 is a bottom plan view of the irrigation drip assembly with a cap having threading stop;

FIG. 8 is a right side elevational view of a stem from the irrigation drip assembly with a cap having threading stop;

FIG. 9 is a left elevational view of the stem from the irrigation drip assembly with a cap having threading stop;

FIG. 10 is a front elevational view of the stem from the irrigation drip assembly with a cap having threading stop;

FIG. 11 is a back elevational view of the stem from the irrigation drip assembly with a cap having threading stop;

FIG. 12 is a perspective view of a cap from the irrigation drip assembly with a cap having threading stop;

(Continued)

FIG. 13 is a cross-section view of the cap from the irrigation drip assembly with a cap having threading stop taken in the direction of line 13-13 of FIG. 12; and,

FIG. 14 is a bottom plan view of the cap from the irrigation drip assembly with a cap having threading stop.

The broken lines in the drawings depict portions of the irrigation drip assembly that form no part of the claimed design.
